2,422,391

FABRIC ANCHORAGE FOR CLOSURES
AND THE LIKERay A. Brenner, New Castle, Ind., assignor to New
Castle Products, New Castle, Ind., a copartner-
ship

Application July 19, 1945, Serial No. 605,991

7 Claims. (Cl. 160—389)

1

This invention relates to an anchorage for a fabric to a plate and more particularly for anchoring a cover to a foldable closure framework of a character such as shown in the prior Patents No. 2,220,939 of Nov. 12, 1940, and No. 2,373,146 of Apr. 10, 1945 and application Serial No. 612,816 of Aug. 27, 1945.

The chief object of this invention is to provide a concealed anchorage for connecting a fabric to a comparatively flat surface support.

While herein the member providing the flat surface is shown terminated near the connection, such member may be extended and in lieu of the termination an aperture may be provided of sufficient size for the purpose required as hereinafter pointed out.

The chief feature of this invention resides in the peculiar connection between the cover or fabric and such member and by a unique anchor or clip.

Other objects and features of the invention will be set forth more fully hereinafter.

The full nature of the invention will be understood from the accompanying drawings and the following description and claims:

In the drawings:

Fig. 1 is a sectional view of the fabric to be supported and the member supporting same, the anchor being shown in side elevation.

Fig. 2 is a top plan view of the aforesaid.

Fig. 3 is a front view of the anchor or clip.

Fig. 4 is a rear view thereof.

In Fig. 1, 10 indicates a supporting member in the form of a wing, hinge plate or strap, etc. having an upper edge 11 and an adjacent aperture 12. 13 indicates a fabric or cover for such member which has secured to its member confronting face as at 14 by sewing and the like a canvas or similar anchor strip 15 and a second strip 16, the latter having aperture 17 therein and an upper edge 18. Strip 15 may be of stiffening character and project above strip top edge 18.

The clip includes a coplanar scroll portion 20. The inner end includes radial portion 21 having transverse extension 22 from which transversely projects prong portion 23. The latter is initially directed toward the plane of the scroll as indicated by dotted lines in Fig. 1.

The other end of the scroll has a coplanar radial outward extension 24 and extending therefrom and substantially parallel to portion 22 is portion 25 which terminates in a hook end 26.

Operation or use is as follows: The wire, resilient clip is nested between strips 15 and 16

and portion 25 with hook 26 extends beyond the edge 18 of strip 16. Lateral portion 22 projects through aperture 17. With the clip thus secured to fabric or cover 13, etc. the prong 23 is passed through aperture 12 in member 17 until it has entirely passed therethrough, but projects at an angle to the plane thereof. Then pressure is applied at the portion 24, etc. and the hook 26 snaps over the end 11 of member 17. Simultaneously therewith prong 23 bears against the face thereof as shown by full lines in Fig. 1. Were it not for this member upon which the prong bears, the prong would assume the dotted line position. However, it is correspondingly resisted which tensions the clip and retains hook 26 in locking or retaining position from which it can only be released by the intentional application of considerable force.

From the foregoing it will be observed that the arrangement is such that whenever and wherever required the clip may be applied in inverted or transverse relation and function properly. Also in all instances the "wear" or friction is taken by strips 15 and 16 and none by fabric 13. Also 25 the clip has, by reason of the coplanar conformation, a large area of strip 16 pressure secured to the member 17, hence, "tearing out" by reason of localized large unit stresses is prevented.

Also it will be noted it is not essential that the 30 clip be applied at an edge of a supporting member for if such member be apertured as at 12 and spaced therefrom a larger aperture be provided and same have an edge comparable to edge 18, that is spaced from aperture 12 in accordance with clip requirements, the invention 35 can be utilized remote from an edge of a support member.

While the invention has been illustrated and 40 described in great detail in the drawings and foregoing description, the same is to be considered as illustrative and not restrictive in character.

The several modifications described herein, as 45 well as others which will readily suggest themselves to persons skilled in this art, all are considered to be within the broad scope of the invention, reference being had to the appended claims.

The invention claimed is:

1. In combination with a cover sheet having an anchor sheet portion secured thereto and a support member having an aperture therethrough and suitably spaced from an edge thereof, an anchor clip interposed between the sheet and sheet portion and having a portion extending

through the latter and said aperture and terminating in an offset portion, said latter portion bearing against said member, and having an opposite portion projecting laterally beyond the sheet portion and bearing on said edge and terminating in a hook portion bearing on said member on the same face thereof as the offset portion.

2. Structure as defined by claim 1 wherein the hook and last mentioned portion are similarly directed.

3. Structure as defined by claim 1 wherein the clip body portion included between the cover and sheet portion is of scroll character.

4. Structure as defined by claim 1 wherein the clip body portion included between the cover and sheet portion is of scroll character, and all portions of which are coplanar.

5. Structure as defined by claim 1 wherein the hook and last mentioned portion are similarly directed, and the clip body portion included be-

tween the cover and sheet portion is of scroll character.

6. Structure as defined by claim 1 wherein the hook and last mentioned portion are similarly directed, the clip body portion included between the cover and strip portion is of scroll character, and all portions thereof are coplanar.

7. Structure as defined by claim 1 wherein an additional sheet portion is provided between the cover and sheet portion and the clip body portion is interposed between the sheet portions.
